UNITED STATES PATENT OFFICE.

EDMUND Z. WILKOSHESKY, OF CHICAGO, ILLINOIS.

CANCELING-STAMP.

938,098.

Specification of Letters Patent.

Patented Oct. 26, 1909.

Application filed August 5, 1909. Serial No. 511,276.

To all whom it may concern:

Be it known that I, EDMUND Z. WILKOSHESKY, a citizen of the United States, residing at Chicago, in the county of Cook 5 and State of Illinois, have invented a new and useful Improvement in Canceling-
Stamps, of which the following is a specification.

My invention relates to improvements in 10 canceling stamps, and especially to that class of stamp used in the postal department for the cancellation of postage stamps applied to packages or boxes and the like.

My object is to provide a revolving self- 15 inking stamp of this class of simple, economical and improved construction, and my device is illustrated in the accompanying drawing, in which—

Figure 1 is a perspective view of my im- 20 proved stamp; Fig. 2, an enlarged view in longitudinal section; and Fig. 3, a view in transverse section taken on line 3 in Fig. 2.

A tube A of requisite length and open at 25 its lower end, as shown in Fig. 2, is provided at its opposite end with a cap α and forms the handle of the stamp. Within the handle is placed an absorbent material B, which extends from slightly below the open end of the tube throughout approximately two- 30 thirds or three-fourths the length of the handle and forms a core, having a chamber b above it, or within the end of the handle, as shown in Fig. 2, to afford an ink-reservoir. The chamber B is filled with liquid 35 ink C and is sealed by a gasket or packing disk α^1 which is confined against the end of the tube by the cap α . A collar D surrounds the handle and is adapted to be adjustably confined thereon through the medium of a 40 set-screw d . Two similar spring-fingers E are secured to the collar between flanges e by screws e^1 , and at their free ends are provided with holes for receiving the trunnions f projecting from the shaft F of the stamp- 45 wheel. This wheel, as shown, comprises a core G of wood, or other suitable material, through which the shaft F passes and to which it is rigidly secured, and a rim g , preferably of rubber, upon the outer surface 50 of which is formed the canceling characters.

In devices of this type it is necessary to 55 frequently change the stamp, for various reasons, and for this purpose the spring-fingers are provided, so that upon spreading them apart the stamp-wheel may be readily removed and another substituted therefor,

which may be as readily adjusted in working position between the fingers.

In use, the device is taken in the hand of the operator and the wheel rolled over a 60 row or a number of stamps on a mail package, by which act the stamps applied thereto may be canceled, regardless of any irregularity in the surface of the wrapper to which the stamps are applied. The ink contained 65 in the chamber percolates or passes through the core by capillary attraction and as the wheel revolves in contact therewith a sufficient quantity thereof is deposited upon the canceling characters of the wheel to produce 70 a clear imprint as the wheel is rolled over the stamps.

In perfecting my device, great difficulty has been experienced in the proper selection 75 of material for the core which would not become hard or crusted at its exposed end, or deteriorate through long use, while permitting of an even distribution or flow of ink therethrough. To avoid these objections and to afford the best possible results, I take 80 a hank of yarn of greater diameter than that of the tube and with a proper instrument draw it into the tube the desired distance. As the yarn is drawn within the tube it is compressed to the desired degree to afford 85 the proper density to the core, and its projecting end is then trimmed off to the requisite length to project slightly from the tube. The handle, or tube, at this end is preferably reamed or curved at its inner edge as 90 shown at h (Fig. 2), so as to allow the core to round out or expand slightly, as shown in that figure, to form a soft and slightly fluffy surface for contact with the wheel.

It has been found in practice that ink 95 used with stamps of this kind flows differently under different temperatures, there being a wide range of difference between its action during winter months and during the summer months. On this account it is 100 very desirable that there be provided a ready adjustment of the wheel to and from the core to vary the contact between them according to conditions and to properly afford the desired coating of ink to the characters 105 of the wheel. As the wheel in revolving gradually wears the core, provision is made also for the adjustment of the wheel to any angle (in a horizontal plane) relative to its previous position, by which the wear of the 110 core may be made uniform. The collar D may be moved along the tube or handle, and

rotated about the same and securely confined thereupon at any desired point by the set-screw *d*, which provides for any adjustment of the roller as occasion demands.

5. What I claim as new, and desire to secure by Letters Patent, is—

1. In a stamp of the character described, the combination of a hollow handle, an ink-supplying core within the handle, a collar 10 revolvably mounted on and adjustably secured to the handle, fingers extending from the collar and a roller rotatably confined between said fingers and against the core, for the purpose set forth.

15. 2. In a stamp of the character described, the combination of a hollow handle containing a chamber, an ink-supplying core within the handle, a collar revolvably mounted on and adjustably secured to the handle, 20 spring-fingers projecting from said collar, and a canceling roller rotatably confined between said fingers and against the core, for the purpose set forth.

3. In a stamp of the character described, 25 the combination of a hollow handle containing a chamber, an ink-supplying core within said handle and composed of strands of

yarn projecting beyond one end thereof, an inking roller, and means for adjusting said roller to and from said core and for adjusting the line of contact of the roller with the core in any direction transversely of the core, for the purpose set forth.

4. In a stamp of the character described, the combination of a cylindrical tube forming a handle having a flaring open end, a compressed ink-conducting core within said tube extending short of one of its ends to form a chamber within the handle and projecting in an expanded form beyond said open end, a collar loosely mounted on the tube, spring fingers attached to and extending from the collar, a printing roller rotatably confined between the fingers, said collar being slidable and rotatable about the tube to adjust the position of said roller relative to the core, and means for holding said collar in adjusted position on the handle, for the purpose set forth.

EDMUND Z. WILKOSHESKY.

In the presence of—

CHAS. E. GAYLORD,
RALPH SCHAEFER.
